CLAIM

The ornamental design for a single panel golf putting training aid, as shown and described.

DESCRIPTION

FIG. 1 is perspective view of the single panel golf putting training aid of the instant invention having a flexible transparent single panel;

FIG. 2 is a front end view thereof;

FIG. 3 is a rear end view thereof;

FIG. 4 is a top plane view thereof;

FIG. 5 is a bottom plane view thereof;

FIG. 6 is an inverted left side view thereof;

FIG. 7 is a right side view thereof; and,

FIG. 8 is a perspective view of a second embodiment of the single panel golf putting training aid.
